[57] CLAIM

The ornamental design for a toy vehicle, as shown and described.

DESCRIPTION

FIG. 1 is a front, top and left side perspective view of a toy vehicle showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and

FIG. 8 is an exploded perspective view thereof similar to that of FIG. 1 with the handle bar in detachably removed position.
